ABSTRACT: A four-high rolling mill is provided with backup roll bending on the lower backup roll only. The compensating bending moment is applied to the roll by means of controllable pressure applying means operably engaged with neck portions of the roll outboard of the bearing chocks and with a stiff beam extending beneath the housings and projecting outwardly therefrom. A four-high mill can be designed and erected without provision for backup roll bending and by later positioning the stiff beam beneath the housings, backup roll bending can be applied to the lower backup roll.

his ATTORNEY

ROLLING MILLS

This invention relates to rolling mills having a pair of work rolls and a pair of backup rolls, such mills being known as four-high mills.

The work rolls of a four-high rolling mill are positioned between the pair of backup rolls which reinforce the smaller diameter work rolls and resist the tendency of the work rolls to bend when metal to be rolled enters the gap between them and produces a load, known as the rolling load, on the work rolls. When the rolling load is very large even the relatively massive backup rolls tend to bend to some extent and this causes the rolled metal product, usually in the form of sheet or strip to be of nonuniform shape, that is the product varies in the thickness across its width with the edges thinner than the center.

It is known to provide controllable pressure applying means operably engaged with the mill housings and neck portions of both backup rolls outboard of their supporting bearing chocks for impairing on both of the rolls a bending moment which compensates for bending of the backup rolls and the work rolls due to forces imposed thereon during a rolling operation. The controllable pressure applying means take the form of hydraulic piston and cylinder assemblies and due to the very high forces which are involved, the assemblies and due to the very high forces which are involved, the assemblies are of considerable size and add considerably to the cost of the mill. Furthermore it is necessary to provide extra stiff mill housings which are capable of withstanding the forces imposed thereon during backup roll bending and again this adds to the cost of the mill.

Many rolling mill operators are not prepared to pay the considerable extra cost of a four-high rolling mill having provision for backup roll bending on both backup rolls and would prefer to purchase a mill without provision for backup roll bending but to which backup roll-bending equipment could be applied at a later date if the need for such equipment arises. With the known backup roll bending arrangement where the pressure-applying means act between the mill housings and the necks of the backup rolls, this is not possible unless the mill housings are initially supplied "oversize." That is, the mill housings are designed to withstand the backup bending forces which will eventually be imposed on them. This means that the initial cost of the housings is greater than for an equivalent mill which is not designed to have backup roll bending. If the mill operator eventually decides not to purchase the extra backup roll-bending equipment to modify his mill then the extra initial cost of the mill housings is wasted. A mill operator seeking to purchase a mill which can subsequently be converted for backup roll bending on both backup rolls also has a further problem regarding the backup rolls which he purchases. If he purchases conventional backup rolls without extended necks then these rolls are useless and have to be replaced with rolls having extended necks when the mill is converted for backup roll bending.

It is an object of the present invention to provide a rolling mill in which at least some of the above-mentioned difficulties are overcome.

According to a first aspect of the present invention a rolling mill has a pair of housings, upper and lower work rolls and upper and lower backup rolls supported in bearing chocks mounted in windows defined by said housing said lower backup roll having a neck portion at each end thereof extending outwardly of the bearing chocks of the roll and controllable pressure applying means operably engaged with said neck portions outboard of the bearing chocks and with a stiff beam extending beneath the housings and projecting outwardly therefrom for imposing on said roll a bending moment to compensate for bending of at least that roll due to the forces imposed thereon during a rolling operation.

Since the roll-bending forces are taken in the main by the stiff beam which extends beneath the mill housings then the housings themselves do not have roll-bending forces exerted

upon them and accordingly can be of smaller dimensions than would be the case if the bending forces acted directly on the housing. This means that a four-high rolling mill not designed for the use of backup roll bending can be adapted to subsequently receive roll bending on the lower backup roll.

In accordance with a second aspect of the present invention, for a rolling mill having a pair of housings, upper and lower work rolls and upper and lower backup rolls supported in bearing chocks mounted in windows defined by said housings, an attachment comprises a stiff beam adapted to extend beneath the housings with end portions of the beam projecting outwardly of the housings and a pair of hydraulic piston and cylinder assemblies mounted one on each of said end portions of the beam, and operably engageable with neck portions at each end of the lower backup roll outboard of the bearing chocks of that roll for imposing on said roll a bending moment to compensate for bending of at least that roll due to the forces imposed thereon during a rolling operation.

It is not an operation of great difficulty to position the stiff beam beneath the housings of an existing rolling mill. The housings are mounted on a concrete foundation and part of the foundation can be broken away to enable the beam to be slid into position without the mill being moved. If the possibility of adding backup roll bending on the lower backup roll is envisaged when the mill is installed, a channel large enough to receive the beam can be made in the foundation when the foundation is laid. Furthermore, the stiff beam could be positioned in the foundation before the mill is positioned on it thereby avoiding the necessity of breaking away part of the foundation at a later date. In any event, as shown in the drawing, the beam contacts the housings inward of its opposite ends. If the beam is never used, its initial cost is wasted but this is considerably less than making the mill housing oversize.

If the backup roll bending is subsequently applied to the lower backup roll of a mill then a new lower backup roll provided with extended neck portions is required, but the original roll is not wasted as this can be used as a spare for the upper backup roll.

By providing compensatory bending on the lower backup roll only, the shape of the product rolled by the mill is not necessarily uniform but it is more uniform than when no compensatory roll bending is provided. For many uses of strip or sheet produced by mill having compensatory roll bending on one roll, the shape is acceptable whereas the shape of sheet or strip from the same mill when no compensatory roll bending is provided would not be acceptable.

In order that the invention may be more readily understood, it will now be described, by way of example only, with reference to the accompanying drawing which is an elevation, partly in section of a rolling mill in accordance with one embodiment of the invention.

A rolling mill has two massive spaced apart housings 1 and 2. Each housing defines a window 3. A pair of large diameter backup rolls 4 and 5 are supported at each end in bearing chocks slidably mounted in the windows 3. The chocks of the upper backup roll 4 are indicated by reference numeral 6. A pair of work rolls 7 and 8, of smaller diameter than the backup rolls are disposed between the backup rolls and are supported at their ends in bearing chocks (not shown) positioned in the windows. A mill top 9 extends between the housings and supports conventional screw down equipment which includes screws 11 which act against the chocks 6. By rotating the screws the vertical position of the upper backup roll relative to the housings can be adjusted.

The lower backup roll 5 is provided with roll-bending equipment to apply a bending moment to the roll to compensate for bending of at least that roll due to the forces imposed thereon during a rolling operation. The roll-bending equipment comprises a stiff beam 12 which may be of fabricated construction and of box section and which extends beneath the housings 1 and 2 and projects outwardly from each housing. The housings are secured to a concrete foundation not shown and the beam 12 may be positioned in the foundation. A pair of

hydraulic piston and cylinder assemblies 13 and 14 have their cylinders rigidly secured to the respective end portions of the beam which project outwardly from the housings. The piston in each cylinder is connected through a piston rod 15 to a bearing housing 16 mounted on an extended neck portion 17 of the lower backup roll. The bearing housings 16 are outboard of the bearing chocks in the housing.

In use, without the piston and cylinder assemblies being actuated, the backup rolls bend as shown in an exaggerated form by the broken lines when metal 18 to be rolled passes through the gap between the work rolls and applies a rolling load to the rolls. By supplying hydraulic fluid under pressure to the cylinders of the assemblies 13 and 14, the piston rods 15 apply a bending moment to the lower backup roll which causes the roll to bend in the opposite direction to that caused by the rolling load. By adjusting the ending forces applied to the roll by the piston and cylinder devices, the bending of the roll due to the rolling load can be compensated for. The bending forces act between the roll necks and the beam 12 and the bending forces do not act upon the screws 11.

The screws 11 experience the rolling load and when, as in the known arrangement, the upper backup roll is provided with compensatory roll bending then the roll-bending forces for the upper backup roll also act on the screws. This means that the screws experience both the rolling and the bending forces and this can cause wear to take place in the screw-operating means if an attempt is made to rotate the screws during operation of the mill. By applying roll bending only to the lower backup roll this serious difficulty is considerably lessened. Furthermore hydraulically operable extensible means in the form of a pair of hydraulic piston and cylinder assemblies 19 can be interposed one between the lower end of each screw 11 and the chocks of the upper backup roll. The screws 11 can then be used to provide coarse adjustment of the roll gap when the mill is not rolling and the assemblies 19 can be energized to provide fine adjustment of the roll gap when the mill is in use.

In accordance with the provisions of the patent statutes, I

have explained the principle and operation of my invention and have illustrated and described what I consider to represent the best embodiment thereof.

I claim:

- 5 1. A rolling mill having a pair of spaced apart housings each defining a window, upper and lower work rolls supported in bearing chocks mounted in said windows, upper and lower backup rolls supported in bearing chocks mounted in said windows, said lower backup roll having neck portions at each end 10 extending outwardly of the bearing chocks, a further bearing each of said neck portions, a stiff beam positioned beneath said housings parallel to the longitudinal axes of the rolls and projecting outwardly beyond said housing and having portions contacting said housings inward of said further bearings and a 15 pair of vertical members extending normal to the longitudinal axes of the rolls and engaging the further bearings and rigidly connected to parts of the stiff beam which project outwardly beyond the housings, said members each including an hydraulically operable piston and cylinder device for adjusting the axial length of the member between the further bearing and the stiff beam.
- 20 2. For a rolling mill having a pair of housings, upper and lower work rolls and upper and lower backup rolls supported in bearing chocks mounted in windows defined by the housings, the lower backup roll having neck portions at each end 25 extending outwardly of the bearing chocks and a further bearing on each of said neck portions an attachment comprising a stiff beam arranged to be positioned beneath the housings parallel to the longitudinal axis of the rolls and projecting outwardly beyond the housings and having portions contacting said housings inward of said further bearings, and a pair of vertical members extending normal to the longitudinal axes of the rolls and engaging the further bearings and rigidly connected to parts of the stiff beam which project outwardly beyond the 30 housings, said members each including an hydraulically operable piston and cylinder device for adjusting the axis length of the members between the further bearing and the stiff beam.
